(57) **CLAIM**

The ornamental design for an electronic cigarette section with mouthpiece as shown and described.

DESCRIPTION

FIG. 1 is a perspective view of an electronic cigarette section with mouthpiece;

FIG. 2 is a front view of the electronic cigarette section with mouthpiece;

FIG. 3 is a rear view of the electronic cigarette section with mouthpiece;

FIG. 4 is a left side view of the electronic cigarette section with mouthpiece;

FIG. 5 is a right side view of the electronic cigarette section with mouthpiece;

FIG. 6 is a top view of the electronic cigarette section with mouthpiece; and,

FIG. 7 is a bottom view of the electronic cigarette section with mouthpiece.

The evenly spaced broken lines in the drawings depict portions of the electronic cigarette section with mouthpiece that form no part of the claimed design; the dash-dot-dash line represents a boundary of the claimed design.
